US00D926699S

(12) **United States Design Patent** (10) Patent No.: **US D926,699 S**
(45) Date of Patent: **** Aug. 3, 2021**

(54) **TERMINAL WIRE CONNECTION PLUG**

(71) Applicant: **Jinyun Reypu Electronic Technology Co., Ltd.**, Lishui (CN)

(72) Inventor: **Dongdong Yi**, Lishui (CN)

(73) Assignee: **Jinyun Reypu Electronic Technology Co., Ltd.**, Jinyun (CN)

(**) Term: **15 Years**

(21) Appl. No.: **29/728,225**

(22) Filed: **Mar. 17, 2020**

(51) LOC (13) Cl. **13-03**

(52) U.S. Cl.

USPC **D13/146**

(58) **Field of Classification Search**

(57) **CLAIM**

The ornamental design for a terminal wire connection plug, as shown and described.

DESCRIPTION

FIG. 1 is a perspective view of a terminal wire connection plug showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

1 Claim, 7 Drawing Sheets
